UNITED STATES PATENT OFFICE.

THOMAS GILBERT-RUSSELL, OF LONDON, ENGLAND.

SCREEN FOR GUN-SIGHTS.

SPECIFICATION forming part of Letters Patent No. 621,066, dated March 14, 1899.

Application filed December 23, 1897. Serial No. 663,174. (No model.)

To all whom it may concern:

Be it known that I, THOMAS GILBERT-RUSSELL, a subject of the Queen of Great Britain, residing at Neasden, London, in the county 5 of Middlesex, England, have invented certain new and useful Improvements in Sighting Devices for Firearms, of which the following is a full and complete specification, such as will enable those skilled in the art to which it applies 10 pertains to make and use the same.

This invention relates to sighting devices for firearms; and it has special relation to improvements in holders for fixing and adjusting a disk or screen such as that shown in Letters Patent No. 309,342, dated December 15 16, 1884.

Heretofore some difficulty has been experienced in applying the disk or screen to firearms so that it can be readily placed in position for use and folded up and otherwise moved so as not to form an obstruction when out of use; and the object of my present invention is to provide a simple and improved holder which will effectively obviate the 25 above-named objections.

The invention is fully disclosed in the following specification, of which the accompanying drawings form a part, in which—

Figure 1 is a side elevation of a portion of 30 a rifle of the Martini-Henry type, showing my improved holder for applying the screen or disk thereto, the said screen being shown in its raised position for use when firing. Fig. 2 is a plan view of the construction shown in Fig. 1. Figs. 3 and 4 are sectional views taken, respectively, on the lines 3 3 and 4 4, Fig. 2. Fig. 5 is a detail plan view of the holder, showing the screen turned down out of use. Fig. 6 is a side elevation of a portion 40 of a Mannlicher rifle, showing the construction and arrangement of my improved holder which I employ for applying the screen to firearms of this type. Fig. 7 is a plan view of the form of construction shown in Fig. 6. Fig. 8 is a transverse sectional view taken on the line 8 8, Fig. 7. Fig. 9 is a side elevation showing the construction of my improved holder when applied to a rifle of the Winchester type. Fig. 10 is a sectional view taken 45 on the line 10 10, Fig. 9. Fig. 11 is a side

elevation showing the form of holder I employ in the application of my invention to a double-barrel sporting rifle or gun. Fig. 12 is a sectional view taken on the line 12 12, Fig. 11. Fig. 13 is a sectional view taken on the line 13 13, Fig. 12. Fig. 14 is a side elevation of a form of construction similar to that shown in Fig. 11, but the holder being hinged so that it can be turned down out of use. Fig. 15 is a sectional view taken on the line 15 15, Fig. 14. Figs. 16 and 17 are detail elevations, at right angles, of the holder shown in Figs. 14 and 15. Figs. 18 and 19 are elevations at right angles, showing a further modification in the form of the holder 65 illustrated in Figs. 14 to 17, inclusive.

In the drawings forming part of this specification the separate parts of my improvement are designated by the same letters of reference in each of the views, and in said 70 drawings, *a* designates the screen, which may be formed of leather, india-rubber, or other flexible or suitable material.

My improved holder embodies an arm *b*, divided or forked, as shown at *c*, to receive 75 the screen *a*, the screen being held in the arm by a set-screw *d*, which also serves for clamping the screen in any position to which it may be adjusted.

In a rifle of the Martini-Henry type, as illustrated in Figs. 1 to 3, inclusive, the arm *b* is provided with a pivot-pin *e*, carried in bearings *f f* on a base-plate *g*. This base-plate for a rifle of the Martini-Henry type is of such a shape that it can be applied to the upper 80 surface of the barrel, as clearly shown in Fig. 3. A spring *h* is carried by the base-plate *g*, and flats *i i* are formed upon the pivot-pin *e*, (see Fig. 4,) against which flats one end of the spring bears to hold the arm *b* in its upward and downward positions, the other end of the spring being attached to the base-plate *g*. 85 90

In the application of my improved holder to a rifle of the Mannlicher type, as shown in 95 Figs. 6 to 8, inclusive, the base-plate *g* is constructed so that it can be applied to the side of the frame. (See Fig. 8.) This form or construction of the holder preferably has a narrow kerf or slit *d'* at its base, which per- 100

mits the set-screw to draw or clamp the fork together, and thus firmly hold the leather or flexible screen in either position. The base-plate is provided with a shoulder g' , below which extends a side plate or tang g^2 , adapted to be secured to the side of the frame by means of a fastening-screw g^3 or in any other suitable manner. The spring h is arched and is preferably provided with studs h' at its ends, which are received by recesses or openings g^4 in the shoulder of the base-plate. The cylindrical base portion of the forked arm bears upon the arched spring and serves to retain the latter in place, and the flats i are formed upon this lower or base portion of the fork and operate with relation to the top of the arched spring.

By the constructions and arrangement as above described, adapted for application to either a rifle of the Martini-Henry type, as shown in Figs. 1 to 3, inclusive, or a rifle of the Mannlicher type, as shown in Figs. 6 to 8, inclusive, the arm b , and with it the screw d , can be turned down and out of use over the barrel, as indicated by the dotted lines in Figs. 1 to 6 and in full lines in Fig. 5, the screen being first turned upon the screw d into the position shown by the dotted lines in Fig. 3.

30 The construction of parts and the general form as above described for Mannlicher rifles are also adapted for convenient and effective application upon other modern repeating rifles of various types and on military rifles 35 as now generally used.

In rifles which have a flat-sided frame, such as the Winchester type, as illustrated in Fig. 9, I dispense with the base-plate g and pivot the arm b upon a pin e , secured to the side of the frame, the arm being of a general shape or contour, as shown, adapted to enable the screen when turned down out of use to lie or rest upon the top of the barrel, as in the constructions before described. The arm b for 45 this type of rifles is extended below the pin e , as at b' , the spring h being arranged to bear against the edge of the said part b' , which latter is provided with the flats i , against which the said spring bears when the arm b 50 is in its raised or lowered positions, the arm b being thus maintained in such positions.

In its application to a double-barrel gun, as shown in Figs. 11 and 12, the arm b is inclined outwardly and upwardly and is either 55 straight, as shown by the dotted lines in Fig. 12, or curved, as shown by the full lines in the said figure, whereby it can be fixed in a hole or recess l in the solid part of the breech and serve to carry the screen a in the proper 60 position for use. The screen is fixed in the arm b by the screw d . To provide for a tight retention of the arm b in the hole or recess l , the arm is preferably divided at its lower end, so 65 as to act as a spring. The arm is also pre-

vented from twisting or turning when inserted in the hole l by means of an end tooth m , which enters a corresponding notch. In this construction of the holder the arm b is withdrawn from the hole or recess l when the screen is 70 not required for use.

In Figs. 14 and 15 I have shown a construction in which the arm b is formed of two parts hinged together, the lower part b^2 being provided with a screw-thread, so that it can be 75 fixed in the hole l , which is correspondingly screw-threaded. The lower end of the upper part of the arm b may be bifurcated, so that it will embrace the head of the part b^2 at the hinged joint. To provide for the rigid retention of the arm b , and with it the screen a , in proper position when turned up for use, I prefer to provide a pin l' , having a rounded end which projects slightly beyond one face of the head of the part b^2 and enters a hole l^2 80 in one side of the fork. The upper part of the arm b may be provided with a kerf or slot, as at b^3 , which renders the fork somewhat elastic, so that when the fork is turned down, as shown in Fig. 14, the sides of the 85 fork will be sprung apart as the pin l' is disengaged from the hole l^2 . When the screen is again turned up into position for use, the pin l' will again engage the hole l^2 under the spring action of the fork and hold the arm b , 90 and with it the screen a , rigid.

In some cases I dispense with the hinge in the form of holder shown in Figs. 14 and 15, the device being simply constructed and arranged so that the arm b can be unscrewed 100 and withdrawn from the hole l when not required for use, this modified construction being shown in Figs. 18 and 19.

The use of the disks or screens for which my improved holder is especially adapted has 105 heretofore been inconvenient and subject to many disadvantages by reason of the essential positions which such disks or screens must take when in use, and my present holder is designed to obviate these disadvantages by 110 providing a convenient and effective method of attachment for the application and use of the disk or screen under various circumstances.

Having fully described my invention, I 115 claim as new and desire to secure by Letters Patent—

1. The combination with a forked arm adapted for attachment to a firearm of a sight-screen situated between the sides of the fork, 120 and means for clamping the sides of said fork upon said sight-screen.

2. The combination with a forked arm mounted in pivotal connection with a firearm and adapted to fold or turn with relation 125 to the same upon its pivot, of a sight-screen situated between the sides of said fork, and means for clamping the sides of the fork upon the sight-screen.

3. The combination with a forked arm piv- 130

totally connected with a firearm, and a spring for holding said forked arm in its adjusted position with relation to the firearm, of a sight-screen situated between the sides of the fork, and means for clamping the sides of the fork upon the sight-screen.

5 In testimony that I claim the foregoing as

my invention I have signed my name, in presence of the subscribing witnesses, this 7th day of December, 1897.

THOMAS GILBERT-RUSSELL.
